(57) **CLAIM**

The ornamental design for a spotlight, as shown and described.

DESCRIPTION

FIG. 1 is a front elevation view of a spotlight according to one embodiment of the present disclosure;

FIG. 2 is a right side view of the spotlight of the embodiment of FIG. 1, the left side view being the mirror image thereof; FIG. 3 is a rear perspective view of the spotlight of the embodiment of FIG. 1;

FIG. 4 is a rear elevation view of the spotlight of the embodiment of FIG. 1;

FIG. 5 is a front perspective view of the spotlight of the embodiment of FIG. 1 in a different position relative to FIG. 1;

FIG. 6 is a front perspective view of the spotlight of the embodiment of FIG. 1 in a different position relative to FIG. 1;

FIG. 7 is a front perspective view of the spotlight of the embodiment of FIG. 1 in a different position relative to FIG. 1;

FIG. 8 is a front elevation view of a spotlight according to another embodiment;

FIG. 9 is a right side view of the spotlight according to the embodiment of FIG. 8, the left side view being the mirror image thereof;

FIG. 10 is a rear perspective view of the spotlight according to the embodiment of FIG. 8;

FIG. 11 is a rear elevation view of the spotlight according to the embodiment of FIG. 8;

FIG. 12 is a front perspective view of the spotlight according to the embodiment of FIG. 8 in a different position relative to FIG. 8;

FIG. 13 is a front perspective view of the spotlight according to the embodiment of FIG. 8 in a different position relative to FIG. 8;

FIG. 14 is a front perspective view of the spotlight according to the embodiment of FIG. 8 in a different position relative to FIG. 8;

(Continued)

FIG. 15 is a front elevation view of a spotlight according to another embodiment;

FIG. 16 is a right side view of the spotlight according to the embodiment of FIG. 15, the left side view being the mirror image thereof;

FIG. 17 is a rear perspective view of the spotlight according to the embodiment of FIG. 15;

FIG. 18 is a rear elevation view of the spotlight according to the embodiment of FIG. 15;

FIG. 19 is a front perspective view of the spotlight according to the embodiment of FIG. 15 in a different position relative to 15;

FIG. 20 is a front perspective view of the spotlight according to the embodiment of FIG. 15 in a different position relative to FIG. 15; and,

FIG. 21 is a front perspective view of the spotlight according to the embodiment of FIG. 15 in a different position relative to FIG. 15.

The dotted lines showing portions of a spotlight are provided for the purpose of illustrating environment and form no part of the claimed design.
